UNITED STATES PATENT OFFICE.

SAMUEL LOWY, OF NEW YORK, N. Y.

OFFICE PARTITION.

Application filed March 7, 1925. Serial No. 13,711.

My invention relates to the construction of partitions, such as are put up in offices and similar spaces, and more particularly to the pilasters forming part of such partitions.

In the present day construction of partitions of this character, the pilasters have to be nailed to the ceiling or otherwise secured thereto in a way which not only tends to deface the ceiling, but makes the removal of the partition or its extension cumbersome. Besides, wood of which such partitions are usually made shrinks, and it often becomes necessary to raise a partition, and in such a case, with the present construction, one is compelled to tear the partition to pieces, involving much labor and leading to much defacement. Nor is the defacing confined to the ceiling. The present type of partition has to be nailed or screwed to the floor also, again adding to the labor and defacement of the room when it is desired to move or to remove the partition.

In my invention, all of the aforesaid drawbacks of the prevailing type of partitions are eliminated. The pilasters are not nailed to the ceiling, but are held in firm contact therewith by pressure. When the partition is removed, the ceiling is not defaced. When the wood shrinks, the partition may be raised to the necessary height without removing nails and screws, merely by turning certain extension members in the pilasters until they make contact with the ceiling, when they are again locked in this position. Likewise, there is no nailing or screwing of the partition to the floor. The partition rests on the floor by virtue of its own weight. All adjustments are easily made and all parts are interchangeable. Other purposes and advantages of my invention will become apparent from the detailed description thereof which follows.

Referring to the drawings, Figure 1 is a front view of my partition when it does not extend all the way to the ceiling; Figure 2 is a front view of my invention when the partition is raised up to the ceiling; Figure 3 is a vertical section through a pilaster of my partition; Figure 4 is a cross section along the line 4—4 of Figure 2, showing a detail of the upper end of the pilaster extension; Figure 5 is a cross section along the line 5—5 of Figure 2 showing the interconnection of ceiling strip, cross rail and pilaster extension; Figure 6 is a cross section

along the line 6—6 of Figure 2, showing the connection between the extension of the pilaster and the adjacent glass panels; Figure 7 is a cross section along the line 7—7 of Figure 3, showing the connection between the pilaster and the adjacent partition sections; and Figure 8 is a cross section along the line 8—8 of Figure 3 showing the manner of connecting the partition sections or panels to the pilaster and floor strip.

The structural elements of my invention, as disclosed in the aforesaid drawings, will now be enumerated. In all of the figures, 1 denotes a partition, composed of pilasters 2 and partition sections or panels 3, the pilasters 2 being extensible and comprising a hollow main post 4 and an extension post 5, this extension post 5 being concealed in the hollow post 4 in Figure 1 and raised in Figure 2. The main hollow post 4 is made up of the facings 6, 6, and the fillers 7, 7, the facings 6 having vertical grooves 8 within which the fillers 7 fit tightly. Other vertical grooves 9 in the facings 6 provide means for the movement therein of the extension post of the pilaster, as further below explained. On the floor 10 are laid metal plates 11 having sharp edged flanges 12 adapted to sink into the floor under the weight of the partition 1. Between the base plates 11 and the partition are floor strips 13, grooved at 14 for the reception of the lower edges of the partition sections 3. On the floor strips 13 are placed the wooden blocks 15, within the hollow main post of the pilaster, and on top of the block 15 rests a metal base plate 16 into which is fitted a vertical threaded post 17. This threaded post 17 extends upwards within a few inches from the top of the main hollow post 4. A tubular post 18 surrounds the threaded post 17 and is provided near its lower end with internal threads, as, for instance, by means of a nut 19, the threads of the tubular post 18 cooperating with the threads of the post 17. A collar or flange 20 is fitted around the tubular post near its lower end or this collar may, as in the drawing, form a part of the nut 19, the nut 19 being fixed to the post 18 by means of a pin 21. Surrounding the tubular post 18 is a metal guide box 22 grooved at 23 to receive the collar 20, said collar 20 being free to rotate in said groove 23. The box 22 is preferably hollow, to reduce its weight, and made up of two parts to allow its insertion in place. On top of the box 22

rests the extension post composed of the facings 24 for the tubular post 18. These facings 24 are adapted to slide in the grooves 9 of the hollow post 4 and are free to slide 5 along the tubular post 18. The facings 24 are formed in a way to permit the joining thereto of glass panels 25 which are held in place by the molding 26. Near the upper end of the tubular post 18, it is provided 10 with perforations 27, whose function will be later explained. A plug 28, preferably of metal, closes the upper end of the tubular post 18. In the plug 28 is swivelled a U shaped member or angle 29, having a journal 30. The plug 28 has perforations registering with the perforations 27 of the tubular post 18, and a hole 31 through the journal 30 of the swivelled member 29 is adapted 15 to register with one or another of the perforations in the plug 28 and tubular post 18, permitting the insertion of a pin 31' therethrough to lock the swivelled member against rotation relatively to the tubular post 18. In the U angle of the swivelled member 29 rests a ceiling strip 32, which may be recessed in the usual manner to present a uniform plane surface throughout. A cross rail 33 lies under the ceiling strip 32, and a cornice 34 finishes up the top of the 20 partition and holds the ceiling strip 32, cross rail 33 and facings 24 of the extension post together by means of screws 35.

The operation of my device will now be briefly explained. We will first consider a 25 partition that does not extend to the ceiling, as shown in Figure 1. In this case the extension parts of the pilasters remain concealed in the main hollow posts and the partition is put up by joining together the interchangeable elements, i. e. the pilasters, 30 partition sections, floor strips and plates, and finishing rails and moldings, in standard fashion in so far as the joining of the partition sections or panels to the pilasters 35 is concerned, but without nailing or screwing the partition to the floor. The weight of the partition, which is comparatively greater than that of ordinary wooden partitions because of the metal parts enclosed 40 in the hollow pilasters, is sufficient to force the sharp edged flanges of the floor plates into the floor even when the latter is of cement. It is not necessary to actually force the plates into the floor to such an extent 45 that the floor is defaced thereby, a slight impress into the floor being generally sufficient, when the partition is not of great length. When the length of the partition 50 is great, it is better to extend some of the pilasters to the ceiling in order to hold the partition in place. The extending of the pilasters and of the partition will now be explained.

60 The extension part of the pilaster comprises, first, the tubular post 18, and, second,

the facings 24 therefor. To extend the pilaster, the tubular post 18 is taken hold of, and raised by causing it to turn on the threaded post 17 by a screw motion. To facilitate this raising, a pin or handle may be inserted into the perforations 27 near the upper end of the post 18, using this pin or handle as a lever. When the tubular post reaches the ceiling, a ceiling strip is laid into the U shaped member, after which the post 18 is forced upwards until it exerts considerable pressure on the ceiling. In order to prevent the U shaped member from turning it is best to have the ceiling strip pass through two or more successive pilaster extensions in the same manner, while the unscrewing of the tubular post is prevented by locking it in the position abutting on the ceiling, which may be accomplished by passing a pin 31' through the hole 31 in the journal 30 of the swivelled member 29 and one of the perforations in the tubular post and plug. To provide for the case when exact registry of the hole 31 with the perforations 27 in the post may not be effected, a shim 36 may be used between the top surface of the plug 28 and the bottom surface of the U shaped angle 29. While the tubular post 18 is being raised, the collar 20 turns in the groove 28 of the guide box 22 and raises the box, which, in turn, raises the facings 24 upwards. At the moment when the tubular post abuts on the ceiling, the facings 24, which do not quite reach the upper end of the post, in order to permit the taking hold thereof, as explained, will leave an uncovered part of the tubular post. It would, of course, be a simple matter to fit an extra piece of facing to the uncovered part of the post, but it is preferable to raise the facings 24 which are slidable on the tubular post, until they entirely cover the tubular post, after which they are made to hold in place by securing thereto the cornice 34, which at the same time secures together the ceiling strip 95 and cross rail.

Any unevenness of the floor may be corrected either by proper thickness of the floor strips at various points, or by adjusting the thickness of the blocks 15. The material, except the floor and base plates, may be wood throughout, but the threaded post and the tubular post are preferably of metal. Of course, the entire partition may be of metal.

It will be seen that the partition is firmly held in position by the floor plates at the bottom and by the pressure of the pilasters against the ceiling on top, without the necessity of nailing or screwing any part of the partition to either floor or ceiling. It will also be seen that all adjustments of height, whether called for by shrinking of the wood, or by changing to another location with a different ceiling, may be effected without the use of nails and screws and without defacing 130

the floor or ceiling. Nor is my construction limited to walls between floor and ceiling. The principle of holding a wall in position by the pressure of the posts against the 5 surfaces on which they abut is equally applicable to cases where a wall or partition is to be built between any two planes. The planes need not even be parallel. Thus, in the case where one of the surfaces on which the posts 10 abut is a dome, I may still use my construction, with some modification which is obvious to those skilled in the art. In general, I do not wish to be limited to the specific structure illustrated in the drawings, and it 15 is to be understood that any addition, omission or modification may be effected in the application of my invention within the knowledge of those familiar with the art that would naturally suggest itself, without detracting 20 from the spirit or scope of my invention.

I claim:

1. An extensible pilaster comprising a main hollow post, a threaded post fixed at the base thereof and extending vertically within 25 said hollow post, a tubular post surrounding said threaded post and having threads cooperating with the threads thereof, a pilaster extension between said tubular post and said main hollow post, and means for raising said 30 pilaster extension when said tubular post is caused to rotate on said threaded post.

2. An extensible pilaster comprising a main hollow post provided with internal vertical guides, a body fitted thereinto at the 35 base thereof, a threaded post fitted into said body and extending upward therefrom within said hollow post, a tubular post coaxial with and enclosing said threaded post, said tubular post being provided with 40 threads at its lower end cooperating with the threads of said threaded post, a facing for said tubular post adapted to slide along said vertical guides, and means for raising said facing when said tubular post is caused 45 to rotate on said threaded post.

3. An extensible pilaster comprising a main hollow post provided with internal vertical grooves, a block fitted thereinto at the base thereof, a base plate on said block, 50 a threaded post fitted into said base plate and extending upward therefrom within said hollow post, a tubular post coaxial with and surrounding said threaded post, said tubular post being provided with internal 55 threads cooperating with the threads of said threaded post, a collar on said tubular post, a guide box around said tubular post fitted into said hollow post, a circular groove in said guide box within which said collar may 60 freely rotate, a facing for said tubular post resting on said guide box and adapted to slide along said vertical grooves and along said tubular post, perforations in said tubular post near its upper end, a plug closing 65 said upper end and having perforations

registering with the perforations in said tubular post, a U shaped member swivelling in said plug, a hole through the journal of said swivelling member adapted to register with one of said perforations in said tubular 70 post and plug, and a pin through said hole and said perforations registering therewith.

4. A partition comprising a plurality of extensible pilasters such as described in claim 3 and partition sections between and 75 joined to said pilasters.

5. In a partition, a plurality of extensible pilasters such as described in claim 3, said pilasters being extended to the ceiling, and a ceiling strip through and fitted into the 80 several U shaped members forming part of the structure of said pilasters.

6. In a partition, a plurality of extensible pilasters such as described in claim 3, said pilasters being extended to the ceiling, a 85 ceiling strip through and fitted into the several U shaped members forming part of the structure of said pilasters, a cross rail under said ceiling strip, and a cornice adapted to hold said cross rail and ceiling 90 strip together.

7. In a partition, a plurality of extensible pilasters such as described in claim 3, said pilasters being extended to the ceiling, a ceiling strip through and fitted into the U 95 shaped members forming part of the structure of said pilasters, a floor strip under said partition, and a plate between the floor and said floor strip provided with sharp edged flanges adapted to sink into 100 said floor.

8. The combination with a partition comprising a plurality of pilasters and a corresponding number of partition sections between and joined to said pilasters, of floor 105 strips under said partition, grooves in said floor strips adapted to receive the lower edges of said partition sections, and plates between the floor and said floor strips provided with sharp edged flanges adapted to 110 sink into said floor.

9. An extensible pilaster comprising a main hollow post, an extension post within said hollow post, an extension member adapted to be raised by a helical motion, and means for raising said extension post when said extension member is raised. 115

10. A partition comprising a plurality of extensible pilasters and a corresponding number of partition sections between and joined to said pilasters, each pilaster comprising a main hollow post, an extension post within said hollow post, and an extension member adapted to be raised by a helical motion; means for raising said extension posts when said extension members are raised; and means for raising said partition by adding sections thereto and connecting said additional sections to said extension posts and to the original partition sections. 120 125 130

11. In an extensible pilaster between a floor and a ceiling, a main hollow post resting on said floor, an extension member therein, means for raising said extension member to and causing it to exert pressure on said ceiling, and independent means for holding said pilaster in position by locking the raised extension member.
12. In a partition between a floor and a ceiling, a plurality of interchangeable, extensible pilasters, each pilaster having a main hollow post resting on said floor and an extension member therein; means for raising said extension members to and causing them to exert pressure on said ceiling; and means for holding said partition in position by locking the raised extension members.
13. In a space between a floor and a ceiling, a main post resting on said floor, an extension member for said post movable longitudinally with respect thereto, a ceiling strip on said ceiling, means for raising said extension member to said ceiling strip, and means, co-operating with said ceiling strip, for locking said extension member in said raised position.
14. In a partition, a pilaster comprising a stationary post, an extension member movable longitudinally with respect thereto, and a separate facing movable with said member and adapted to form an extension of said post.
15. A partition comprising a plurality of extensible pilasters and a corresponding number of partition sections between and joined to said pilasters, each pilaster comprising a stationary post, an extension member movable longitudinally with respect thereto, and a facing movable with said member and adapted to form an extension of said post, and means for extending said partition by adding sections thereto and connecting said additional sections to said extension posts and to said original partition sections.
16. In a partition between a floor and a ceiling, a ceiling strip on said ceiling, a post abutting said floor and said ceiling strip, a U shaped member on said post embracing said strip, and means for holding said post in position by pressure on said floor and on said ceiling strip.
17. In a partition between a floor and a ceiling, a ceiling strip on said ceiling, a wall comprising a plurality of posts abutting said floor and said ceiling strip, U shaped members on said posts embracing said ceiling strip, and means for holding said wall in position by pressure of said posts on said floor and on said ceiling strip.
18. In an extensible pilaster, a post, a jacket over said post adapted for longitudinal movement relatively thereto, a collapsible facing for said jacket adapted to be moved therewith, means on said post and on said jacket cooperating to hold said jacket in a fixed position relatively to said post, and means for releasing said jacket for said longitudinal movement.

SAMUEL LOWY.

CERTIFICATE OF CORRECTION.

Patent No. 1,646,651.

Granted October 25, 1927, to

SAMUEL LOWY.

It is hereby certified that error appears in the printed specification of the above numbered patent requiring correction as follows: Page 3, Lines 124 and 125, claim 10, strike out the words "by a helical motion" and insert instead "above said main post"; and that the said Letters Patent should be read with this correction therein that the same may conform to the record of the case in the Patent Office.

Signed and sealed this 20th day of December, A. D. 1927.

Seal.

M. J. Moore,
Acting Commissioner of Patents.
